ELECTRIC ALARM CLOCK

Raymond E. Hutchinson, Bristol, Conn., assignor
to The Sessions Clock Company, Forestville,
Conn., a corporation of Connecticut

Application July 10, 1939, Serial No. 283,540

8 Claims. (Cl. 58—38)

This invention relates to improvements in electric alarm clocks. More especially, the present invention concerns a superior construction and arrangement of the alarm-mechanism and also 5 of the several other units constituting the operating mechanism of an electric alarm clock.

One of the objects of the present invention is to provide a superiorly constructed and arranged 10 electric alarm clock in which the parts comprising the alarm-mechanism thereof are grouped together and consolidated rearwardly of the other operating elements of the clock and in such manner as to secure desirable non-cramping 15 relationship of the parts, together with compact organization thereof.

Another object of this invention is to provide an improved electric alarm clock having the parts thereof constituting propelling-means, power-transmission means, and alarm-mechanism, 20 respectively organized in compact relationship and as individual units, the said units being also compactly related to each other and in such manner as to avoid cramping of the parts of a unit to accommodate parts of another of the 25 units of the clock.

Still another object of the present invention is to secure a superior electric alarm clock, in which the electric motor thereof is arranged between a time-train and alarm-mechanism of the clock, 30 and spaces the said alarm-mechanism rearwardly of the said time-train, the parts of the respective units being organized in compact non-cramped relation and being thereby accessible 35 for repair or replacement, or for cleaning, oiling or similar purposes.

A further object of this invention is to provide a superior electric alarm clock having a time-train substantially enclosed in and supported 40 by a movement-frame and disposed forwardly of an intermediately-arranged electric motor, the said clock also having alarm-mechanism disposed rearwardly of said electric motor, and the said units being directly or indirectly supported on a forwardly-positioned member of the clock, 45 which also serves as a mounting-plate for the dial of the clock.

Still a further object of the present invention is to provide an improved electric alarm clock 50 in which the parts comprising each of several operating-units may be constructed and assembled before the said units are brought into organized relation to each other, and whereby economical production and assembly are secured and facilitated.

55 Another object of the present invention is to

provide a superior electric alarm clock having the respective operating-units thereof arranged in compact yet non-cramped relation and in which protection of the said parts against damage or breakage is secured, particularly with respect to the time-train and the alarm-mechanism of the clock. 5

With the above and other objects in view, as will appear to those skilled in the art from the present disclosure, this invention includes all 10 features in the said disclosure which are novel over the prior art.

In the accompanying drawings, in which certain modes of carrying out the present invention are shown for illustrative purposes: 15

Fig. 1 is a front elevational view of an electric alarm clock movement-unit embodying the present invention;

Fig. 2 is an enlarged rear elevational view thereof, the alarm-mechanism being shown in 20 operating position;

Fig. 3 is a top or plan view thereof partly in section;

Fig. 4 is an underside or bottom-plan view 25 thereof;

Fig. 5 is a fragmentary sectional view taken on the line 5—5 of Fig. 4;

Fig. 6 is a similar view taken on the line 6—6 of Fig. 2;

Fig. 7 is a perspective view of the hammer; and 30

Fig. 8 is a plan elevational view of the bell, detached.

The particular electric alarm clock herein chosen for the purpose of illustrating the present invention includes a dial 10 and pointer-members, including a seconds-pointer 11, a minute-pointer 12 and an hour-pointer 13, all of which are arranged to be driven about the dial 10 by means to be more particularly described hereinafter. 35

The dial 10, as is especially well shown in Figs. 3 and 4, is carried on the front face of a dial-back plate 14, which preferably is formed to provide a central portion 15 and an outer flange-portion 16, lying in substantially the same plane, 45 the said portions respectively engaging the central portion and the outer portion of the dial 10. The dial-back plate 14 is also provided with a central opening 17, arranged to be aligned with a central opening 18 of the dial 10 for the passage 50 of mounting-means for the said pointers. Intermediate its said central-portion 15 and the outer flange-portion 16, the dial-back plate 14 is provided with an offset-portion 19, which is spaced rearwardly of the dial 10 and is provided 55

with rearwardly-depressed mounting-recesses 20.

To the rear of the dial-back plate 14 a propelling-unit is mounted, which unit, in the embodiment of the invention illustrated, is a self-starting synchronous electric motor, generally designated by the reference character 21, for driving a time-train indicated as a whole by the reference character 22 and disposed forwardly of the electric motor 21 and intermediate the

10 latter and the above described dial-back plate 14.

For the purposes of the present invention, the electric motor 21 need be put briefly described. Electric current from a suitable source may be supplied to leads 23 which pass through openings

15 24 provided in a cup-shaped pole-piece 25 and connect with an energizing-coil, not shown. The said cup-shaped pole-piece extends rearwardly and cooperates with a plate-like pole-piece 26. The pole-pieces 25 and 26 are provided with

20 salient poles 27 and 28, respectively, which, as is clearly shown in Fig. 2, are arranged in interfitting relation. Preferably, certain of the salient poles 27 are shaded by means of suitably-pierced

25 shading-rings 29 formed of copper or the like, which are permanently organized with the cup-shaped pole-piece 25 to produce a rotating field effect and secure a self-starting synchronous motor-structure.

Arranged to be acted on by the rotating field 30 of the motor is a rotor 30 having a forwardly-extending flange 31 which overlies and turns about the interfitted salient poles 27 and 28. The rotor 30 is rigidly secured to a collet 32 and the said collet, in turn, is rigidly secured to the rear end of a rotor-shaft 33. Collet 32, which is rotatable with the rotor 30, extends rearwardly therefrom and carries a double-lift hammer-actuating cam 34, the purpose of which will more fully hereinafter appear, and the rotor-shaft 33, 35 which is rotatable with the collet 32, extends forwardly therefrom, through the motor structure and projects through the forward end wall of the cup-shaped pole-piece 25.

As has been mentioned, the electric motor 21, 40 just above described, is arranged to drive the time-train 22 disposed forwardly of the said motor and between the same and the dial-back plate 14. The time-train 22, as shown, is mainly organized between and within spaced apart front and rear movement-plates 35 and 36 which are of 45 substantially similar construction and constitute a movement-frame for supporting and enclosing the said time-train. The movement-plates 35 and 36 are coupled in spaced relationship by pillars 37, the said movement-frame being supported as a whole on the dial-back plate 14 by 50 means of the externally-threaded forward ends of the pillars 37 which pass through the front movement-plate and through the offset-portion 19 of the dial-back plate 14 and enter the mounting-recesses 20 thereof. Between the front 55 movement-plate 35 and the rear face of the dial-back plate 14, the pillars 37 are provided with spacing-nuts 38, and the extreme forward ends of the pillars 37, located in the mounting-recesses 20, are provided with holding-nuts 39 for rigidly securing the movement-frame to the dial-back plate 14.

The movement-frame, i. e., the movement- 60 plates 35 and 36 and the pillars 37, supported as described on the dial-back plate 14, provides support for the electric motor 21, suitable means such as stud-bolts 40 projecting from the forward end-wall of the cup-shaped pole-piece 25 through the rear movement plate 36 being provided with

5 nuts 41 for rigidly securing the motor 21 in place on and at the rear of the said rear movement-plate 36. The rotor-shaft 33 of the motor also extends through the rear movement-plate 36 and projects into the space between the movement-plates 35 and 36 of the movement-frame and cooperates with and forms part of the time-train 22, which is mainly organized within the said movement-frame.

Preferably, the time-train 22 comprises a 10 worm-drive-and-spur-gear assembly, the rotor-shaft 33, projecting within the movement-frame, being provided therein with a first worm 42 which meshes with and drives a first worm-wheel 43 rigidly mounted on a shaft 44. As is particularly 15 well shown in Figs. 3 and 4, the shaft 44 is journaled at its respective opposite ends in bracket-arms 45—45 secured to the rear movement-plate 36 and projecting forwardly into the space between the movement-plates 35 and 36. Adjacent 20 the end opposite the first worm-wheel 43, the shaft 44 has rigidly mounted thereon a second worm 46 which, in turn, meshes with and drives a second worm-wheel 47 rotating about an axis parallel with but eccentric with respect to the 25 axis of the rotor-shaft 33 and perpendicular to the axis of the first worm-wheel 43 and the second worm 46.

The second worm-wheel 47 is rigidly secured 30 on a center-arbor or seconds-shaft 48 extending between the movement-plates 35 and 36 and journaled therein, the said center-arbor also projecting through the central openings 17 and 18 of the dial-back plate 14 and the dial 10, respectively, and carrying the seconds-pointer 11 at the 35 outer end thereof.

At the rear end of the center-arbor 48 a spur-pinion 49 is rigidly attached thereto to engage with and drive a spur-wheel 50 rigidly secured on a shaft 51, the last also bearing in the movement-plates 35 and 36. The shaft 51 is also provided with a spur-pinion 52 which meshes with a minute-wheel 53 and the said minute-wheel is frictionally mounted on a hub 54 which, in turn, is mounted with freedom for rotation on the center-arbor 48. The hub 54 is normally coupled to the minute-wheel 53 for rotation therewith, but with freedom for being turned with respect thereto, by a friction-washer 55 which may be held in place on the hub 54 by means of a collet 56. The frictionally-coupled hub 54 is provided with a minute-sleeve 57 which extends through the front movement-plate 35 and also projects through the central openings 17 and 18 of the dial-back plate 14 and the dial 10, and has the 55 minute-pointer 12 secured thereto at the outer end thereof.

Immediately forwardly of the front movement-plate 35 and between the same and the dial-back plate 14, the minute-sleeve 57 is provided with 60 a spur-pinion 58 rigidly mounted thereon and meshing with and driving a suitably mounted dial-wheel 59. The dial-wheel 59 has a dial-pinion 60 rigidly secured thereto, and the latter engages with and drives an hour-wheel 61 rigidly 65 carried on an hour-sleeve 62. In turn, the hour-sleeve 62 is mounted with freedom for rotation on the minute-sleeve 57 and projects forwardly through the openings 17 and 18 in the dial-back plate 14 and the dial 10, and carries the hour-pointer 13 at the outer end thereof.

Also positioned between the front movement-plate 35 and the dial-back plate 14 and driven by the said hour-wheel 61, is a spur-pinion 63 which meshes with and drives an alarm-control 70

spur-wheel 64 rigidly mounted on an alarm-control shaft 65 for the purpose as will herein-after appear.

The alarm-mechanism is generally designated by the reference character 66 and is mounted at the rear of the electric motor 21, being spaced by the latter rearwardly of the time-train 22. As shown, the said alarm-mechanism includes an alarm-mounting-plate 67, which is spaced rearwardly of the motor 21 and is preferably supported from the dial-back plate 14 by means of two or more pillars 68. The pillars 68 are each threaded at the respective opposite ends thereof, the forward ends of the pillars extending through the offset-portion 19 of the dial-back plate 14 and each being provided with a nut 69 (see Fig. 4) for rigidly securing the respective pillars in place on the dial-back plate 14. From the said dial-back plate the pillars 68 extend rearwardly past the time-train 22 and the electric motor 21, the rear ends thereof extending through the alarm-mounting plate 67 which is rigidly secured thereto by means of securing-nuts 70 to hold the said alarm-mounting plate in spaced relationship with respect to the motor 21.

The above mentioned alarm-mounting plate 67 has a bracket 71 riveted thereon, the said bracket carrying a bell 72 which is secured to the bracket 71 by a screw 74 and nut 75.

Cooperating with the bell 72 is a hammer or striker, preferably formed of sheet metal, which is generally designated by the reference character 76 and includes a hammer-body 77 and an integral resilient hammer-arm 78. The hammer 76 is also carried by the alarm-mounting plate 67, the said hammer being pivotally mounted on a stud 79 projecting from the front face of the said alarm-mounting plate and passing through an opening 80 in the hammer-body 77, whereby the hammer 76 is pivotally mounted on the alarm-mounting plate 67 between the latter and the rear of the electric motor 21.

In its preferred form, shown particularly well in Fig. 7, the hammer 76 is bent to provide an end-portion 81 which is angularly related to the hammer-body 77. The hammer-arm 78, which is mainly separated from the said hammer-body, is also bent to provide an L-shaped end-portion 82. The L-shaped portion 82 parallels two angularly-related sides of the end-portion 81 of the hammer-body 77, one of the legs of the L-shaped portion 82 and a third side of the end-portion 81 being integrally united. The hammer 76 is thus provided with a hammer-arm 78 having capacity for flexing and vibrating with respect to the hammer-body 77, and the said hammer-arm, at the outer free end thereof opposite its union with the hammer-body 77, is provided with a hammer-head or striker-head 83, which may be welded, soldered or brazed thereto, but which is preferably formed integral with the hammer-arm 78.

As will be understood, it is intended that the hammer-head 83 strike the bell 72 to ring the same and that this operation take place only on selected occasions. Accordingly, the hammer-body 77 is provided with a rearwardly-offset arm 84 which carries a forwardly-projecting actuator-pin 85, and the said actuator-pin, as will presently appear, may be brought into position to engage the hammer-actuating cam 86 rotating continuously at the rear of the electric motor 21, to swing the hammer 76 with respect to the bell 72. The hammer-body 77 is also provided with a rearwardly-extending finger 88 which is engaged by a sheet-metal hammer-

spring 87 secured to a stud 88 projecting from the front face of the alarm-mounting plate 67, the said spring 87 constantly urging the hammer 76 into engagement with the hammer-actuating cam 86.

The hammer-body 77 is also provided with a cam-stud 89 adjacent the end-portion 81, which cam-stud projects rearwardly therefrom and is arranged to coact with a disk-like alarm-control cam 90 carried by the alarm-control shaft 65 before referred to, whereby the said alarm-control cam is operable from the herein described time-train 22. The alarm-control shaft 65 has its forward end journaled in the dial-back plate 14 and extends rearwardly therefrom, like the mounting-pillars 68, past the time-train 22 and the electric motor 21, and adjacent its rear end the said alarm-control shaft passes through a hub 91 which bears in the alarm-mounting plate 67. The hub 91 projects at the front and at the rear of the alarm-mounting plate 67, and its forward end is spun over to rigidly secure the said alarm-control cam 90 thereto between the said alarm-mounting plate and the electric motor 21. At its rear end, the hub 91 is similarly spun over to rigidly secure a setting-disk 92 thereto, the said setting-disk being provided with a rearwardly-projecting setting-finger 93, which is preferably formed integral therewith.

The hub 91 having the setting-disk 92 and the alarm-control cam 90 rigidly mounted thereon is frictionally coupled to the alarm-control shaft 65 by a friction-washer 94, which may be of spider-form, and which bears on the rear face of the setting-disk 92. The friction-washer 94, in turn, is engaged by the inner one of two nuts 95, 96 which are threaded on the reduced rear end of the alarm-control shaft 65.

Thus, the hub 91, with the setting-disk 92 and the alarm-control cam 90 rigidly secured thereto, may be rotated with respect to the alarm-control shaft 65, for the purpose of adjusting or setting the alarm-mechanism. The setting-finger 93 may be grasped and turned and preferably cooperates with an index graduated to hours and intervals thereof, which index is not shown herein and which may be a separate wheel or disk, for example, or may be inscribed on the back of a casing.

More particularly, with respect to adjustment of the alarm-mechanism, the periphery of the alarm-control cam 90, which may also together with the setting-disk 92, be turned with respect to the alarm-control shaft 65, is provided with an alarm-release notch 97 therein, which may be caused to register with and receive the cam-stud 89 of the hammer 76 at any particular and desired phase of the revolution of the alarm-control cam 90 caused by the operating time-train 22.

Also arranged to act on the hammer 76, to position the same with respect to the above-described alarm-control cam 90, is an alarm-shut-off plunger 98. The shut-off plunger 98 and the operating positions thereof are clearly shown in Fig. 5, in which it will be observed that the said plunger is arranged to slide in a sleeve or bushing 99 which is mounted in the alarm-mounting plate 67 and extends forwardly and rearwardly thereof. At the rear of the said alarm-mounting plate, the bushing 99 is provided with a transverse slot 100 which intersects the axial passage formed therein, the said slot receiving a spring 101 which is adapted to frictionally engage and cooperate with grooves 102 formed on

the shut-off plunger 98 to hold the latter in either its "on" or "off" positions. At its forward end, the plunger 98 is provided with a conical-tip 103 which may be pushed into or pulled from an aperture 104 in the hammer-body 77, whereby the hammer 76 may be cammed away from the alarm-control cam 90, or may be released for operation.

Assuming that the shut-off plunger 98 has been moved into its forward or "on" position, shown in broken lines in Fig. 5, the conical-tip 103 will have entered the aperture 104 of the hammer-body 77 and will have caused the hammer 76 to shift about its pivot 79. In the shift of the hammer 76 the actuator-pin 85 thereof will have been caused to be moved out of the path of the continuously-rotated hammer-actuating cam 34. The shifting of the hammer 76 also moves the cam-stud 89 into a position where it will not enter the notch 97 of the alarm-control cam 90.

Current from a suitable source is assumed to be entering the electric motor 21 by way of the leads 23, and the rotor 30 is being synchronously turned. The collet 32 and the rotor-shaft 33 accompany the rotor 30 in its turning movement and the double-lift hammer-actuating cam 34 also rotates continuously therewith. The continuous rotation of the said cam 34 is without effect on the hammer 76 as the actuator-pin 85 of the said hammer has been moved out of the path thereof, but the rotation of the said rotor-shaft 33 is effective with respect to driving the time-train 22.

By means of the first worm 42 carried at the forward end of the rotor-shaft 33, located between the movement-plates 35 and 36, the hereinabove described worm-drive-and-spur-gear time-train 22 is driven to turn the center-arbor 48, the minute-sleeve 57 and the hour-sleeve 62, and these, in turn, cause the seconds-pointer 11, the minute-pointer 12 and the hour-pointer 13 to revolve about the dial 10 at the respective rates of one revolution a minute, one revolution an hour, and one-twelfth of a revolution an hour.

Also rotating with the above-mentioned hour-sleeve 62 is the hour-wheel 61, which drives the spur-pinion 63, and the said spur-pinion engages with and drives the alarm-control wheel 64 and thereby the alarm-control shaft 65, on which the said alarm-control wheel is rigidly mounted. As the alarm-control shaft 65 turns, the hub 91 frictionally coupled thereto and the alarm-control cam 90 and the setting-disk 92 rigidly mounted on the hub 91, also turn and these parts also revolve at the rate of one-twelfth of a revolution an hour. The revolution of the said hub 91, alarm-control cam 90 and setting-disk 92 will be without effect at this time, particularly as concerns the said alarm-control cam, which revolves without affecting the now-retired hammer 76.

When on occasion it is desired to set or adjust the alarm-mechanism to a selected time, the setting-finger 93, and hence the setting-disk 92, may be turned with respect to the index before referred to but not shown herein. The setting-disk 92 accompanies the setting-finger 93 in the said movement, as does the hub 91, to which the setting-disk 92 is rigidly secured, and the alarm-control cam 90 rigidly mounted on the hub 91. The parts just referred to, because of the frictional coupling provided by the friction-washer 94, turn with respect to the alarm-control shaft 65. A result of this movement is to shift the notch 97 of the alarm-control cam 90 to its proper

position relative to the time selected for the alarm to function.

Following the above step, or prior thereto if desired, the shut-off plunger 98 may be withdrawn into its "off" position (see Fig. 5), withdrawing the conical-tip 103 from the aperture 104 in the hammer-body 77. The hammer 76, when freed of the restraint imposed thereon by the conical-tip 103 bearing therein, will, under the urge of the spring 87, swing about its pivot to bring the cam-stud 89 of the said hammer into the path of, and to be engaged by, the periphery of the alarm-control cam 90, now being slowly driven by the alarm-control shaft 65 from the time-train 22.

As the said alarm-control cam 90 slowly rotates, the periphery thereof, engaging with the cam-stud 89, prevents the hammer 76 from swinging, under the urge of the spring 87, into position to bring its actuator-pin 85 into the path of the continuously-rotating hammer-actuating cam 34. When the rotation of the alarm-control cam 90 registers the notch 97 therein with the cam-stud 89 of the hammer 76, the latter responds to the urge of the spring 87 to further swing the hammer 76 about its pivot to drop the cam-stud 89 into the notch 97, to thus engage the actuator-pin 85 with the hammer-actuating cam 34.

Inasmuch as the hammer-actuating cam 34 is provided with double-lift portions and its speed of rotation is several hundred revolutions a minute, the engagement of the actuator-pin 85 with the said cam will cause the latter to move the hammer 76 outwardly against the urge of the spring 87. The hammer 76, under the urge of the spring 87, will then be sharply returned to again be moved outwardly by the rapidly-rotating hammer-actuating cam 34. The described rapid back-and-forth oscillations of the hammer 76 cause the resilient hammer-arm 78 thereof to flex and vibrate with respect to the hammer-body, which results in the hammer-head 83 rapidly and sharply striking against the adjacent wall of the bell 72.

At any time during the period in which the hammer 76 is oscillating as above described, this action of the hammer may be discontinued by pressing the shut-off plunger 98 inwardly to its "on" position, whereby the conical-tip 103 will enter the aperture 104 to shift the hammer 76 and the actuator-pin 85 away from the hammer-actuating cam 34 and, more particularly, to move the cam-stud 89 out of the notch 97 of the alarm-control cam 90.

The operation of the said alarm-control cam 90 may, of itself, bring about the discontinuance of the oscillations of the hammer 76. This will occur when the shut-off plunger 98 has not been pressed to cause the cam-stud 89 to be withdrawn from the notch 97 for, as the alarm-control cam 90 continues to be slowly driven by the time-train 22, the cam-surface of the said notch will cause the cam-stud 89 to gradually ride out of the notch 97 and up on the periphery of the alarm-control cam 90, to thus hold the hammer 76, with the actuator-pin 85 thereof, positioned out of the path of the hammer-actuating cam 34. However, under these conditions and in order that the lapse of a twelve-hour period will not result in another operation of the alarm-mechanism, the shut-off plunger 98 is also to be pressed inwardly, whereby the hammer 76 is thereafter held out of operating position by the conical-tip of the said plunger 98 engaging in the hammer-body 77.

As will be apparent, the construction and arrangement of the parts herein shown and described are such as to secure the carrying out of the operations above set forth in a superior and more effective manner. It is found to be particularly desirable to mount the alarm-mechanism at the rear of the electric motor 21, and that the said alarm-mechanism be separated by the said electric motor from the forwardly-disposed time-train 22.

The parts comprising the several operating-units, and especially the alarm-mechanism, may be completely assembled independently of each other before being assembled in their respective 15 positions to form a complete alarm clock structure. The parts comprising the respective units are compactly arranged, yet the relationship of the parts and of the units is such that the desired compactness is secured without cramping. 20 A feature of the arrangements is that provision is made for ready access to parts for inspection, repair, or replacement thereof, and at the same time the parts are assembled in protected relationship, whereby necessity for repair or re- 25 placement is substantially minimized. It is also of advantage to have the respective operating-units, that is, the time-train 22, the electric motor 21 and the alarm-mechanism 66, all supported directly or indirectly on the plate 14, 30 which also carries the dial 10 at the front thereof.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are 40 intended to be embraced therein.

I claim:

1. An electric alarm clock comprising: a dial-back plate; a time-train; a movement-frame enclosing and supporting said time-train and mounted on said dial-back plate; an electric motor located at the rear of said movement-frame and carrying a continuously-rotatable hammer-actuating cam at the rear thereof, the said electric motor also including a rotary member operatively connected at its forward end with said time-train; time-indicating mechanism including rotary means operatively connected with said time-train; and alarm-mechanism including an alarm-mounting plate mounted at the rear of said electric motor, a bell carried by said alarm-mounting plate, and a hammer pivoted thereon, the said alarm-mechanism also including an alarm-control cam operable from said time-train and engageable with said hammer to shift the same into and out of the path of the continuously-rotatable hammer-actuating cam; the said movement-frame and time-train being mounted at the front of said electric motor and between the same and the said dial-back plate, and the said alarm-mechanism being mounted at the rear of the electric motor and being spaced thereby rearwardly of the said movement-frame and time-train.

2. An electric alarm clock comprising: a dial-back plate; a time-train; a movement-frame enclosing and supporting said time-train and mounted on said dial-back plate; an electric motor located at the rear of said movement-frame and carrying a continuously-rotatable hammer-actuating cam at the rear thereof, the said elec-

tric motor also including a rotary member operatively connected at its forward end with said time-train; time-indicating mechanism including rotary means operatively connected with said time-train; and alarm-mechanism including an alarm-mounting plate, mounting-pillars secured to said dial-back plate and extending rearwardly across said movement-frame, time-train, and electric motor, the said mounting-pillars being secured to the said alarm-mounting plate to support the same on said dial-back plate and at the rear of said electric motor, a bell carried by said alarm-mounting plate, and a hammer pivoted thereon, the said alarm-mechanism also including an alarm-control cam operable from said time-train and engageable with said hammer to shift the same into and out of the path of the continuously-rotatable hammer-actuating cam; the said movement-frame and time-train being mounted at the front of said electric motor and between the same and the said dial-back plate, and the said alarm-mechanism being mounted at the rear of the electric motor and being spaced thereby rearwardly of the said movement-frame and time-train.

3. An electric alarm clock comprising: a dial-back plate; a time-train; a movement-frame enclosing and supporting said time-train and mounted on said dial-back plate; an electric motor located at the rear of said movement-frame and carrying a continuously-rotatable hammer-actuating cam at the rear thereof, the said electric motor also including a rotary member operatively connected at its forward end with said time-train; time-indicating mechanism including rotary means operatively connected with said time-train; and alarm-mechanism including an alarm-mounting plate, mounting-pillars secured to said dial-back plate and extending rearwardly across said movement-frame, time-train, and electric motor, the said mounting-pillars being secured to the said alarm-mounting plate to support the same on said dial-back plate and at the rear of said electric motor, a bell carried by said alarm-mounting plate, and a hammer pivoted thereon, the said alarm-mechanism also including an alarm-control shaft journaled at its forward end in the said dial-back plate and operable from said time-train, the said alarm-control shaft extending rearwardly to and through the said alarm-mounting plate, an alarm-control cam frictionally coupled on said alarm-control shaft adjacent the said alarm-mounting plate and engageable with said hammer to shift the same into and out of the path of the continuously-rotatable hammer-actuating cam; the said movement-frame and time-train being mounted at the front of said electric motor and between the same and the said dial-back plate, and the said alarm-mechanism being mounted at the rear of the electric motor and being spaced thereby rearwardly of the said movement-frame and time-train.

4. An electric alarm clock comprising: a dial-back plate; a time-train; a movement-frame enclosing and supporting said time-train and mounted on said dial-back plate; an electric motor located at the rear of said movement-frame and carrying a continuously-rotatable hammer-actuating cam at the rear thereof, the said electric motor also including a rotary member operatively connected at its forward end with said time-train; time-indicating mechanism including rotary means operatively connected with said time-train; and alarm-mechanism including

- an alarm-mounting plate mounted at the rear of and in spaced relation to said electric motor, a bell carried by said alarm-mounting plate, and a hammer pivoted on the forward face of said 5 alarm-mounting plate and positioned between the same and the rear of said electric motor, the said hammer being shiftable to engage with said continuously-rotatable hammer-actuating cam, the said alarm-mechanism also including an 10 alarm-control cam operable from said time-train, the said alarm-control cam also being mounted between the said alarm-mounting plate and the rear of said electric motor and being engageable with the said hammer to shift the same into and 15 out of the path of said continuously-rotatable hammer-actuating cam; the said movement-frame and time-train being mounted at the front of said electric motor and between the same and said dial-back plate, and the said alarm-mechanism being mounted at the rear of the electric 20 motor and being spaced thereby rearwardly of the said movement-frame and time-train.
5. An electric alarm clock comprising: a dial-back plate; a time-train; a movement-frame enclosing and supporting said time-train and mounted on said dial-back plate; an electric motor located at the rear of said movement-frame and carrying a continuously-rotatable hammer-actuating cam at the rear thereof, the 25 said electric motor also including a rotary member operatively connected at its forward end with said time-train; time-indicating mechanism including rotary means operatively connected with said time-train; and alarm-mechanism including 30 an alarm-mounting plate, mounting-pillars secured to said dial-back plate and extending rearwardly across said movement-frame, time-train and electric motor, the said mounting-pillars being secured to the said alarm-mounting plate to 35 support the same on said dial-back plate at the rear of and in spaced relation to said electric motor; a bell carried by said alarm-mounting plate, and a hammer pivoted on the forward face of said alarm-mounting plate and positioned between the same and the rear of said electric motor, the said hammer being shiftable to engage 40 with said continuously-rotatable hammer-actuating cam, the said alarm-mechanism also including an alarm-control cam operable from said time-train, the said alarm-control cam also being mounted between the said alarm-mounting plate and the rear of said electric motor and being engageable with the said hammer to shift the same into and out of the path of said continuously-45 rotatable hammer-actuating cam; the said movement-frame and time-train being mounted at the front of said electric motor and between the same and said dial-back plate, and the said alarm-mechanism being mounted at the rear of the electric 50 motor and being spaced thereby rearwardly of the said movement-frame and time-train.
6. An electric alarm clock comprising: a dial-back plate; a time-train; a movement-frame enclosing and supporting said time-train and mounted on said dial-back plate; an electric motor located at the rear of said movement-frame and carrying a continuously-rotatable hammer-actuating cam at the rear thereof, the said electric 55 motor also including a rotary member operatively connected at its forward end with said time-train; time-indicating mechanism including rotary means operatively connected with said time-train; and alarm-mechanism including an alarm-mounting plate, mounting-pillars secured 60 to said dial-back plate and extending rearwardly across said time-train and movement-frame and across said electric motor, the said mounting-pillars being secured to said alarm-mounting plate to support the same on said dial-back plate and at the rear of said electric motor, a bell carried by said alarm-mounting plate, and a cooperating hammer, the said alarm-mechanism also including an alarm-control cam operable from 65 said time-train, the said hammer including a hammer-body pivoted on said alarm-mounting plate, and a hammer-arm integrally united at one end thereof with the hammer-body and having capacity for flexing with respect thereto to provide a vibrating hammer-arm, the said hammer-body being provided with a cam-pin and with an actuator-pin, and the said alarm-control cam being provided with a notch for receiving the said cam-pin whereby the hammer is shiftable to 70 bring the actuator-pin thereof into the path of said continuously-rotatable hammer-actuating cam to be lifted thereby and cause the hammer to be lifted with respect to the said bell.
8. A hammer for an electric clock comprising: 75 a hammer-body having an angularly-related end-portion, and a integral hammer-arm having a hammer-head at one end thereof, the said hammer being constructed and arranged to be pivotally mounted in an electric clock to be 80

turned alternately into positions to engage a portion of the hammer with a continuously-rotating member of the electric clock and to cause the said hammer-head to strike a bell of 5 alarm mechanism of the electric clock, and being also constructed and arranged to be shifted about its pivotal mounting out of the path of the continuously-rotating member of the electric clock by the engagement therewith of a manually-10 operable transversely-movable shut-off member,

and the said hammer-arm being also provided with portions thereof bent to extend in transverse directions parallel to and in spaced relation to said angularly-related end-portion of said hammer-body and being united with the said angularly-related end-portion of the hammer-body, the said hammer-arm having capacity for flexing and vibrating with respect to the said hammer-body. 5
